J. L. McATREE

VANITY CASE

Filed June 30, 1925

UNITED STATES PATENT OFFICE.

JOHN L. McCATREE, OF NEW YORK, N. Y., ASSIGNOR, BY MESNE ASSIGNMENTS, TO
SCOVILL MANUFACTURING COMPANY, OF WATERBURY, CONNECTICUT, A CORPO-
RATION OF CONNECTICUT.

VANITY CASE.

Application filed June 30, 1925. Serial No. 40,480.

This invention relates to certain improvements in small boxes or cases for holding cosmetics and commonly known as vanity cases.

5 These cases are usually carried in a handbag, pocketbook, or in a pocket of the user's apparel, and consequently are as small as practicable. To be saleable these cases must be of an attractive appearance. These 10 cases are, furthermore, provided with a cover, which in many instances is associated with the case by a hinge.

It is the special object of the present invention to produce a box or case of this type 15 which shall be small and compact, and in which the box and its cover are pivotally associated on a hinge which is so arranged as to be invisible when the box is closed, so that an attractive box is produced, and one 20 in which there are no projecting parts likely to catch in the clothing, or in articles carried in the handbag or the like. It is a further object of the invention to produce a box in which two cosmetics, as powder 25 and rouge, may be carried each in a separated compartment having a cover which may be opened simultaneously to expose the contents.

With these and other objects not specifically referred to in view, the invention consists in certain novel arrangements, parts, and combinations which will be described in connection with the accompanying drawings in which.

35 Figure 1 is a plan view of the box in closed position;

Figure 2 is a side view of the same;

Figure 3 is a top view, partly in section showing the box open, with one form of interior construction which may be adopted;

40 Figure 4 is a central vertical section of the closed box, the section being taken on line 4-4 of Fig. 1;

Figure 5 is a section similar to Fig. 4, the section being taken on line 5-5 of that figure;

Figure 6 is a detail view, partly broken away, showing the hinge assemblage;

50 Figure 7 is a side view of the parts shown in Fig. 6 looking in the direction of arrow 7 of that figure;

Figure 8 is a detail sectional view, the

section being taken on line 8-8 of Fig. 3, and

Figure 9 is a view of an abutment which 55 may be used to keep the parts in position.

Referring now to these drawings in detail, the box chosen to illustrate the invention is a double box, that is, a box capacitated to hold two kinds of cosmetics, as powder 60 and rouge, either in the form of compacts, or loose. It will be understood, however, that the box shown is merely illustrative, and that as to certain of its features it may be used with but one cosmetic. 65

In the construction shown there is provided a box having a bottom or body 1 and a cover 2, these parts having upwardly and downwardly sloping side walls 3, 4 respectively. The body and cover are pivotally associated on a hinge, and in accordance with the invention this hinge is arranged so as to be invisible when the box is closed. While this may be effected in various ways, in the structure shown the box body 1 is formed with an inturned peripheral flange 5, forming a groove or recess 7. Located in the box body 1 is a pivot point, and what may be termed a hinge carrier. While the specific structure of these parts may be somewhat varied, as shown, the box bottom or body is divided by a partition 8 into two compartments 9, 10, these compartments being of different sizes, the compartment 9 being intended for rouge and the larger compartment 10 being intended for powder, this construction being adopted as more powder than rouge is ordinarily used. 75

80 The partition 8 is in the form of a plate which rests on the bottom of the box and is held in place by a suitable abutment.

85 This is conveniently formed by an arcuate member, preferably in the form of a piece of spring wire 11 shown in Fig. 9, the ends 12 of the wire pressing against the plate and holding the plate in position in the bottom of the box. This wire is secured in place by springing it under the flange 5 into the groove 7, before referred to. 90

95 In accordance with the invention, the cover 2 is pivotally associated with the bottom 1 by a hinge which is concealed so that 100

the hinge does not show when the box is closed.

The particular box shown is a double box, that is, a box capacitated to hold two cosmetics, each of the cosmetic holding compartments being covered. Where a box of this type is to be used, the partition may be conveniently used as the pivot support for carrying the cover 2 and certain parts associated therewith to which the cover is hinged. In the particular construction illustrated the small compartment 9 is provided with a cover 13, this cover being hinged to the partition 8 in any suitable manner. As shown, the cover 13 is provided with a centrally located knuckle 14, and on each side of the knuckle 14 the top edge of the partition is bent to form knuckles 15 and 16, the partition being centrally cut away between the knuckles 15 and 16 to provide room for knuckle 14, this latter being conveniently formed by bending in the edge of the cover plate 13. These parts are associated on a pintle 17 which passes through the knuckles and forms a pivotal connection between the parts. In order to prevent sidewise movement of the partition and the associated parts in the box and to strengthen the construction, anchoring means are provided which, as shown, consist in turning in the ends of the partition, as indicated at 18 in Fig. 3, these turned in ends having a snug engagement under the flange 5 and in the groove 7. With this construction any displacement of the partition and its associated parts is prevented.

The cover 2 may be pivotally associated with the cover 13 where this latter cover is used, and the hinge by which this is effected is so arranged that it is concealed when the parts are closed, as shown in Fig. 1. Furthermore, with this construction when the cover 2 is opened and raised it also acts to raise the cover 13 so as to expose the small compartment covered thereby. While the particular construction for effecting this may be somewhat varied, in the construction shown the cover 13 is provided with a narrow depending flange 20 which is centrally cut away, as indicated at 21 in Fig. 6, and on each side of which is provided a knuckle 22.

The cover 2 is provided with a downwardly extending flange 23 which has a snug engagement with the inner edge of the flange 5 of the bottom 1, before referred to. This flange is cut away, as indicated at 24 in Fig. 7, and in the cut away portion in a plane with the flange is formed a knuckle 25. The knuckle 22 and the knuckle 25 are connected together by a pintle 26, so that the cover 2 has a free pivotal movement in the cover 13. The parts are so constructed that the knuckles 22, 25 and the pintle 26 will lie inside

the flange 5 so that when the box is closed these parts are not seen, the box having the appearance illustrated in Fig. 1.

In boxes embodying the invention in its best form, means will be provided for preventing the accidental opening of the cover. While this may be effected in various ways, in the particular construction shown there is provided on the knuckle 25 a projection 27. When the lid is closed this projection is positioned under the flange 5 and holds the cover in position. This projection also acts to assist in positioning the hinge under the flange 5. The closing movement of the cover brings this projection up against the inner surface of the flange, and the projection acts in effect as a cam for giving the cover a slight lateral movement and forcing the parts into position under the flange so that they are entirely concealed thereby, the spring of the metal of which the parts are made permitting this slight movement.

In order that the cover may clear the locking projections 18 on the partition, the flange 23 is formed with cutouts 28 which will permit the cover to close down over the flange.

Any desired means may be employed for opening the cover. As shown, the flange 23 is cut away, as indicated at 29 in Fig. 5, and the metal is slightly bent outwardly to form a projection 30 which may be engaged by a finger of the user to raise the lid. The cover is in the particular box illustrated held closed by the friction between the flange 5 of the bottom and the flange 23 on the cover.

If desired, the cover may be provided with a mirror or other reflecting surface 31, held in place by the usual ring or bezel 32.

With the construction shown and described it will be seen that a very thin box has been provided, and one in which there is provision for two compacts, each in its own compartment, and each of the compartments is provided with a cover, the outer cover covering one of the compartments and the inner cover the other. Furthermore, these covers may be operated to simultaneously open the compartments so that access may be had to either of them, and when the box is closed the hinge uniting the body and the cover is invisible, thus providing a box of attractive appearance with no projecting parts.

While the box has been shown and described in its preferred form, it will be understood that various changes and variations may be made in the specific structure shown and described without departing from the invention as defined in the appended claims.

What I claim is:

1. In a vanity box, the combination of a body having an inturned peripheral flange,

an outer cover for the body, and a hinge pivotally uniting these parts, which hinge lies under the flange of the body and is entirely concealed thereby when the box is closed.

2. In a vanity box, the combination of a body having an inturned peripheral flange, a partition rigidly secured in the body and dividing it into compartments, and an outer cover hingedly associated with the partition by a hinge which lies under the flange of the body and is entirely concealed thereby when the box is closed.

3. In a vanity box, the combination of a body, a partition in the body, means for preventing displacement of the partition, an inner cover hinged to the partition, and an outer cover hinged to the inner cover.

4. In a vanity box, the combination of a body, a partition in the body, an inner cover hinged to the partition, and an outer cover hinged to the inner cover by a hinge which is invisible from the outside of the box when the outer cover is closed.

5. In a vanity box, the combination of a body having an inwardly projecting peripheral flange, and a cover pivotally associated with the body by a hinge which lies under the flange and is concealed thereby when the cover is closed.

6. In a vanity box, the combination of a body having an inturned peripheral flange, a cover, a hinge for pivotally associating the body and the cover, and means for causing the hinge to move under the flange when the cover is closed so as to conceal the hinge.

7. In a vanity box, the combination of a body having an inturned peripheral flange, a cover, a hinge for pivotally associating the body and the cover, means for causing the hinge to move under the flange when the cover is closed, said means including a projection bearing under the flange.

8. In a vanity box, the combination of a box body having an inturned peripheral flange, a partition in the body, a spring wire under the flange and engaging the sides of the partition to prevent displacement of the partition in one direction, means carried by the partition for preventing this displacement in the other direction, an inner cover pivoted to the partition, and an outer cover pivoted to the inner cover.

9. In a vanity box, the combination of a

box body having an inturned peripheral flange, a partition in the box, means engaging beneath the flange for preventing displacement of the partition, an inner cover pivoted to the partition, knuckles on the cover, an outer cover having a knuckle, and a pin connecting the knuckles of the two covers and forming a hinge which lies under the flange when the outer cover is closed.

10. In a vanity box, the combination of a body having an inturned peripheral flange, a cover having a vertical flange adapted for close engagement with the flange of the body when the parts are in closed position, and a hinge pivotally uniting the two parts, said hinge lying under the peripheral flange and concealed thereby when the parts are closed.

11. In a vanity box, the combination of a body, having an inturned peripheral flange, an inner cover in the body, and an outer cover pivoted to the inner edge of the inner cover, the pivot of the outer cover being entirely concealed when the box is closed.

12. In a vanity box, the combination of a body, a rigid member wholly in the body and forming a pivot, and an outer cover hinged in the pivot by a hinge concealed from outside the box when the box is closed.

13. In a vanity box, the combination of a body having an inturned peripheral flange, a partition in the body dividing it into a plurality of compartments, a cover having a vertical flange adapted for close engagement with the flange of the body, cutouts in the flange of the cover to clear the partition walls when the parts are in closed position, and a hinge pivotally uniting the two parts and lying under the flange of the body and concealed thereby when the parts are closed.

14. In a vanity box, the combination of a box body having an inturned peripheral flange, a partition in the body, a spring wire under the flange and engaging the sides of the partition to prevent displacement of the partition in one direction, the pintle carried by the partition having inturned ends for preventing the displacement of the partition in the other direction, an inner cover pivoted on the pintle, and an outer cover pivoted to the inner cover.

In testimony whereof, I have hereunto set my hand.

JOHN L. McATREE.
